AUTOMATIC ELECTRONIC TIMING DEVICE

Samuel S. Hatfield, Dayton, Ohio

Application August 29, 1945, Serial No. 613,413.

5 Claims. (Cl. 89—1:5)

(Granted under the act of March 3, 1883, as amended April 30, 1928, 370 U. S. G. 757.)

1

The invention described herein may be manufactured and used by or for the Government for governmental purposes without payment to me of any royalty thereon.

This invention relates to automatic electronic timing devices.

Conventional means for opening and closing the bomb bay doors of a bombing aircraft requires the use of an electric motor driven crank. This means for opening and closing bomb bay doors requires the bombardier to open the bomb bay doors before the bomb run is started. The act of opening the bomb bay doors so far in advance of actually releasing the bombs, signals to enemy anti-aircraft gunners that such bomb run is about to begin. Since it is well understood in the art, that while on such bomb run, the bombing aircraft must maintain an unswerving course, enemy gunners can, in view of the premature disclosure that the bomber is about to begin its bomb run, more accurately concentrate their fire.

In an effort to overcome the problem presented by opening the bomb bay doors when the bomb run begins, the "pop open" door method was conceived. However, no method was heretofore available for supplying the correct desired lapse of time after the door opening mechanism was actuated by the bomb sight for opening the bomb bay doors, and the actual bomb release time, the release of the bombs being desired as immediately after the bomb bay doors are completely opened as possible. Since, therefore, the usual time for "popping open" the bomb bay doors requires one to one and one-half seconds, depending upon the type of aircraft and the type of door opening mechanism, a predetermined time interval, approximately two seconds, is necessary from the time that the door opening mechanism is triggered by the bomb sight, and actual bomb release, to insure the bomb bay doors being completely opened before releasing the bombs. This predetermined time interval is set up in the bomb sight controls in such a manner that the triggering impulse from the bomb sight to the door opening mechanism occurs by this predetermined interval of time before the desired bomb release point. Other problems which have heretofore not been solved are loss of accuracy in the timing device due to supply voltage fluctuations and humidity, the limitation on the size of components which may be carried in an aircraft, and the requirement that a timing device for releasing bombs a predetermined period of time after the bomb bay doors are opened and closing bomb bay doors a predetermined period of time after

2

the last bomb has been released, operate with extreme accuracy utilizing the low voltage supply generated by the aircraft's power supply. Various other characteristics must be achieved in order that this timing device shall be satisfactory from the standpoint of stability and accuracy of operation and shall be commercially feasible in its construction, as will be more apparent hereafter.

10 It is, therefore, an object of this invention to provide circuit means for permitting extremely accurate timing intervals at any available supply voltage.

Another object is to provide accurate timing intervals under conditions limiting the size of available components and requiring utilization of the low voltage supply from an aircraft generator.

A further object is to provide means for achieving accurate timing intervals for releasing bombs in a bomber aircraft when used in combination with a bomb sight and an intervalometer in a bombing system.

A still further object is to provide circuit means for automatically, electrically, releasing bombs at a predetermined period of time.

Other objects and features of novelty will be apparent from the following description and the annexed drawings, it being clearly understood, however, that the invention is not limited in any way by such description and drawings or otherwise than by the appended claims.

Referring now to the drawings in which similar reference numerals refer to like parts:

Fig. 1 is a block diagram illustrating the interconnection of the components of this invention with other structural elements of a bombing system; and

Fig. 2 is a circuit diagram of a complete bombing system partially schematic, embodying the present invention.

Referring now more particularly to Fig. 1 of the drawings, there is shown in block form a bombing system embodying a preferred form of the present invention. In general, a system includes a bomb sight 10 which is connected to and simultaneously actuates a bomb release timer 11, forming part of timing device 12, and a door opening mechanism 13, for opening the bomb bay doors 53 of a bomber aircraft and delaying the dropping of the bombs for a predetermined period of time after the bomb bay doors commence to open, this delay being sufficient to permit the bomb bay doors to be completely opened before the bombs are released. The bomb sight 10 may be of any preferred type so long as provision is

made therein for closing contacts or otherwise producing an electrical signal at the instant of bomb release and so long as the sight is of such a type that provision may be made for setting ahead the time when the contacts close, or when the electrical signal is given, in order to take care of the time-delay produced by the bomb release timer 11. In the Norden type of bomb sight, an electrical signal is produced by the sight when the aircraft arrives at the proper position for the bombs to hit the target. In this type of sight, the 2-second time-delay provided by the timer 11 may be compensated for by adding two seconds to the time of fall when this data is converted into disc speed which is then set into the sight. This will cause the electrical impulse produced by the sight to occur two seconds prior to the proper time of release of the bombs for hitting the target and thereby compensate for the 2-second delay occurring in timer 11. Alternatively, a bomb sight structure such as that shown in the patent to Inglis, No. 2,105,147, filed January 11, 1938, may be used for compensating for the 2-second time-delay interval. As shown in Fig. 19 of this patent, when the switch 164 is in the position shown in solid lines in the figure, the solenoid 165 will be energized when contacts 151, 156 meet. The solenoid 165 in turn may be arranged to trip any suitable type of a bomb release mechanism. The contacts 151, 156 are the ones normally used in order to cause the bomb to strike the target when the proper constants have been set into the sight. However, by throwing the switch 164 to the dotted line position shown in Fig. 19, the solenoid 165 may be actuated prior to the proper time of release as determined by the contacts 151, 156. With the switch 164 in the dotted line position, the control of the solenoid 165 is switched over to contacts 152, 157 which make contact somewhat earlier than contacts 151, 156. By adjusting contact 157 so that this contact engages contact 152 two seconds ahead of the time when contacts 151, 156 meet, the 2-second time-delay provided by the bomb release timer 11 may be compensated for and the bomb or bombs will be released from the aircraft at the same instant that contacts 151, 156 engage with one another.

Bomb release timer 11 activates an intervalometer 14 of the type described in the copending application of Habig, Ser No. 494,027, filed July 9, 1943, now Patent No. 2,388,686, for triggering a bomb rack 15 to drop a plurality of bombs in a predetermined timed sequence. While intervalometer 14 is operating, each succeeding bomb release triggers bomb bay door closing timer 16, forming the other part of timing device 12. However, since the time interval between each bomb release is much less than the time required for actually causing door closing timer 16 to operate only after the last bomb is released does the door closing timer 16 actually operate to delay operation of the door closing mechanism 17 for a predetermined period of time after the last bomb is dropped, so as to permit the last bomb released to completely clear the bomb bay doors.

Referring now to Fig. 2 of the drawings, the reference numeral 10 represents a bomb sight which is pre-set by the bombardier of a bombing aircraft to trigger the door opening mechanism, for "popping open" the bomb bay doors 53 at a predetermined time during the bomb run and simultaneously energizing relay coil 18 which corresponds to relay coil 165 of Fig. 19 in the patent to Inglis, and which operates to close relay con-

tacts 19 and 20 and open contact 21. The door opening mechanism for "popping open" the bomb bay doors 53 comprises a hydraulic actuating mechanism consisting of solenoid 54 connected to bomb sight 10 and solenoid 54a connected to relay contact 47 which solenoids actuate pilot valve 55 for controlling the flow of hydraulic fluid into either end of servo cylinder 51, depending on whether solenoid 54 or solenoid 54a is energized. Servo cylinder 51 drives piston rod 52a which actuates linkages 52 operably connected to bomb bay doors 53. In deenergized condition of relay coil 18, grid electrode 25 of triode tube 22 and the grid side of capacitor 26 are connected to ground. The cathode side of capacitor 26 is connected to the power supply through resistor 27. Resistor 27 is of such value as to permit rapid charging of capacitor 26 but does not place an appreciable drain on the power supply when contact 20 is closed. In this deenergized condition of relay coil 18, tube 22 is nonconducting since its cathode 23 is at the same potential as its plate 24. When relay coil 18 is energized by bomb sight 10 closing contacts 19 and 20 it remains locked in energized condition since the relay armature associated with contact 19 is connected directly to the power supply through contact 39 of relay coil 36 thus locking contact 20 in closed position. Closing contact 20 connects cathode 23 of tube 22 and the cathode side of capacitor 26 to ground thereby placing the positive cathode side of capacitor 26 at ground potential and disconnecting the grid side of capacitor 26 and grid electrode 25 from ground. Disconnecting the grid side of capacitor 26 and grid 25 from ground places both grid 25 and the grid side of capacitor 26 at negative potential by the amount of the voltage across capacitor 26 which is substantially equal to that of the power supply 28. The capacitor 26 immediately starts to discharge through the power supply and resistors 29 and 30, thus allowing the potential of grid 25 to rise until the cut-off point of tube 22 is reached, at which time the tube begins to conduct. The resulting current flow through relay coil 31 causes the relay to operate to close contact 32 and initiate operation of intervalometer 14. The time-delay interval before actuation of intervalometer 14 is controlled by the values of resistors 29 and 30 and capacitor 26. This interval may be adjusted by changing the value of variable resistor 30. Each release impulse from intervalometer 14 sequentially energizes relay coil 33 closing contacts 34 and 35. When contact 34 is closed, relay coil 36 is energized, closing contacts 37 and 38 and opening contact 39. When relay coil 36 is energized, it remains locked in energized condition since the relay armature associated with contact 37 is connected directly to the power supply through contact 48 of relay coil 46, locking contact 38 in closed position. The opening of contact 39 deenergizes relay coil 18 opening contacts 19 and 20, causing tube 22 to return to its nonconducting state. Contact 35, when closed by energization of relay coil 33 by intervalometer 14, connects the grid 42 of tube 41 and the grid side of capacitor 43 to ground. This capacitor is in a charged condition with the grid side positive, having previously charged through resistor 45; however, the charge will be small because any appreciable build-up of voltage across capacitor 43 is prevented by the conductance of the grid-cathode path of tube 41. When contact 35 closes, condenser 43 discharges through the power supply and resistor 44 and

then charges, with reversed polarity, to a potential substantially equal to that of the power supply. This charging must progress rapidly enough for the negative grid potential to exceed the cut-off value before contact 38 closes and plate potential is applied to tube 41, in order to avoid premature energization of relay coil 46. Deenergization of coil 33 causes lower contact 35 to open and the upper contact to make, thus connecting the cathode side of condenser 43 to ground. The condenser then discharges through the power supply and resistor 45, causing the potential of grid 42 to rise or become less negative with respect to the cathode. However, before the grid potential reaches the cut-off point, coil 33 is again energized by the intervalometer, thus closing contact 35 and causing condenser 43 to rapidly recharge through resistor 44. In other words, the time interval between each bomb release impulse from intervalometer 14 is shorter than the time required for condenser 43 to discharge sufficiently to allow tube 41 to become conducting. After the last bomb is released, however, the coil 33 remains deenergized and contact 35 is open for a sufficient length of time to allow condenser 43 to continue its discharge until the potential of grid 42 has risen to the cut-off point, at which time tube 41 becomes conducting. The plate current of tube 41 in its conducting state energizes relay coil 46 closing contact 47 and opening contact 48. Closing contact 47, energizes solenoid 54a for closing bomb bay doors 53 and opening contact 48 deenergizes relay coil 36 opening contact 38. Opening of contact 38 deenergizes plate 40 of the tube 41 thereby causing the tube to become nonconducting. Capacitor 49 is connected between the power supply end of relay coil 46 and ground, and maintains relay coil 46 in an energized condition long enough to enable contact 47 to energize solenoid 54a to cause complete closing of the bomb bay doors.

Pilot light 50 is connected between the filament lead of tube 41 and ground to indicate to the bombardier the fact that the filaments of tubes 22 and 41 are lighted. Since the filaments of tubes 22 and 41 are connected in series with one another, the lighting of pilot light 50 indicates that the filaments of the tubes are intact and that the cathodes are being heated thereby.

Having thus described my invention, I claim:

1. A bomb control system for bombing aircraft comprising a bomb sight of the type capable of producing an electrical signal preceding the proper instant of bomb release by a predetermined time interval, a set of bomb bay doors, electrically controlled actuating means for said doors, means for applying said bomb-sight signal to said actuating means for opening said doors at the occurrence of said signal, a first delay means for producing a first delay period, means for applying said bomb-sight signal to said first delay means for initiating operation thereof, an intervalometer capable of responding to the application of an electrical signal thereto to produce a fixed number of successive electrical release signals having equal time separation, means connected between said first delay means and said intervalometer for initiating operation of the latter at the end of said first delay period, a bomb rack of the type actuated by an electrical signal to effect bomb release, means connected between said intervalometer and said bomb rack to apply said release signals to said bomb rack, a second

delay means for producing a second delay period exceeding the time interval between the successive release signals produced by said intervalometer, means for applying each of said release signals to said second delay means for initiating operation thereof, and means connected between said second delay means and said bomb bay door actuating means for closing said bomb bay doors at the end of said second delay period.

2. Apparatus as claimed in claim 1 in which said first delay means comprises a first condenser, means providing resistive charging and discharging circuits for said first condenser, a first vacuum tube having its grid and cathode connected to the negative and positive terminals respectively of said first condenser when in its charged condition, and means normally connecting said first condenser in its charging circuit and actuated by said bomb-sight signal to connect said first condenser in its discharging circuit; and in which said means for initiating operation of said intervalometer comprises a current responsive means located in the anode circuit of said first vacuum tube for applying a voltage to said intervalometer when the anode current of said first tube reaches a certain value.

3. Apparatus as claimed in claim 2 in which said second delay means comprises a second condenser, means providing resistive charging and discharging circuits for said second condenser, a second vacuum tube having its grid and cathode connected respectively to the negative and positive terminals of said condenser when in its charged condition, and means normally connecting said second condenser in its discharging circuit and actuated by the release signals from said intervalometer to connect said second condenser in its charging circuit; and in which said means for closing said bomb bay doors comprises a current responsive device in the anode circuit of said second tube for applying a voltage to said electrically controlled door actuating means for closing said doors when the anode current of said second tube reaches a certain value.

4. Apparatus as claimed in claim 3 in which means are provided for holding said means for connecting said first condenser in its discharging circuit, in its actuated condition until the occurrence of the first release signal produced by said intervalometer.

5. Apparatus as claimed in claim 4 in which means actuated by said first release signal from said intervalometer are provided for connecting a source of direct current in the anode circuit of said second vacuum tube, and in which means operated by said current responsive device in the anode circuit of said second tube is provided for disconnecting said source of voltage from said anode circuit upon operation of said current responsive device.
